United States Patent Office

Des. 178,279
Patented July 17, 1956

178,279

LAWNMOWER HANDLE

Clayton K. Cole, Kalamazoo Township, Kalamazoo County, and Dominick A. Saporito, Royal Oak, Mich., assignors to Atlas Press Company, Kalamazoo, Mich., a corporation of Michigan

Application December 22, 1955, Serial No. 39,453

Term of patent 14 years

(Cl. D40—1)

Des. 178,279

PAGE 2

fig. 3

fig. 4

Fig. 5

Figure 1 is a front elevational view of a lawnmower handle, showing our new design.

Figure 2 is a side elevational view of said handle.

Figure 3 is a top plan view of said handle.

Figure 4 is a rear view of the upper portion of said handle.

Figure 5 is a rear elevational view of said handle.

The characteristic features of the lawnmower handle reside in the portions shown in full lines

We claim:

The ornamental design for a lawnmower handle, as shown and described.
